LARS G. NILSON, OF HOBOKEN, NEW JERSEY.

PRIMING-CUP FOR GASOLENE-ENGINES.

1,178,818.

Specification of Letters Patent. Patented Apr. 11, 1916.

Application filed September 18, 1914. Serial No. 862,300.

To all whom it may concern:

Be it known that I, LARS G. NILSON, a citizen of the United States, residing in the city of Hoboken, county of Hudson, State of New Jersey, have invented certain new and useful Improvements in Priming-Cups for Gasolene-Engines, reference being had to the accompanying drawings, illustrative of one particular embodiment of my invention.

10 My invention consists of a priming cup such as is used in gasoline engines, having a quick and ready releasable closure involving peculiar advantages as will hereinafter appear.

15 While features of my invention may be used in other embodiments or combinations, in the preferred form of my invention I produce a cup adapted to hold a small quantity of gasoline to be dripped into the cylinder for the purpose of affording the initial charge of gas for starting, and combined with said cup, a means of closing the gasoline aperture in a secure manner, while the means for closure is at the same time simple and quickly operative, and above all things easily operated under the conditions of use of such articles. While all parts of oil cups or priming cups are liable to be 20 heated, and priming cups, when open, are where an exhaust of hot gases may occur, devices for this purpose heretofore have been difficult to handle or liable to burn or otherwise injure the hands or fingers when being 25 operated. In the embodiment of my invention such danger is eliminated and certain and quick action is made possible, while the closing of the same is equally quick and certain and is effected by such a quick movement of the hand as to avoid the possibility 30 of any inconvenience.

A particular form of my invention is shown in the drawings in which:

35 Figure 1 is a vertical section of the cup showing lever in locked position. Fig. 2 is a side elevation showing in dotted lines a modified base of the cup also lever in locked position and dotted lines in unlocked position. Fig. 3 shows a diagram of the action of the locking lever. Fig. 4 is a part 40 vertical section at right angles to that shown in Fig. 1.

In the particular form illustrated, A is a cup; A' is the interior surface of the cup; B is the threaded end of the cup for attachment to the engine cylinder; B' shows in

dotted outline a modified form of the attaching end of the cup, C is the locking lever; D is the closure or sealing end of the lever; E is a stop to hold the lever in locked position; F is a stop or projection for coöperation with the cup in the unlocking action of the lever; G—G are retaining ears or clips to secure the spring links H to the lever C; H'—H' are pivot ends of the link H securing it to the body of the cup A; J is a recess in the side of the cup body the walls J' of which being adapted for engagement with the spring link H to limit its swinging motion.

45 In Fig. 3 the diagrammatic explanation of the action of this form of my invention, includes the swinging center X of the locking link H, and the position Y of the pivoting center between the locking lever and the locking link when in locked position, and the position Y' when in unlocked position, and Z the effective turning center of the closure end of the lever when locked. The center lines of the lever are shown at c in 50 locked position, c' in unlocked position, while the center line of the spring link is shown at h in locked position, h' in unlocked position; and the arc of movement about the center Z is shown at z, and the arc of 55 movement of the spring lever about its pivot X is shown at x, as it would take place if not stretched owing to the relation of the parts as will be hereinafter described. The line of centers of the swinging pivot of the 60 locking links and the center about which the closure end of the lever C pivots is shown at a.

65 It will thus be seen that the device shown in the drawings comprises a priming cup and relief cock, in which the portion A forms with the interior surface A', a cup adapted to receive a small quantity of gasoline for use to prime an engine, while the other end of the device is threaded as at B so as to be screwed into a tapped hole in the cylinder. Longitudinally through the center is a hole K, to serve as a vent for gases and also to conduct or let the gasoline pass from the cup into the cylinder. As shown 70 in Fig. 2 the end to secure to the cylinder is turned at right angles, the extremity B' shown dotted being a threaded end to screw into the aperture in the cylinder when the hole in the cylinder is horizontal, thereby 75 keeping the cup portion in an upright position adapted to receive and hold gasoline.

The lever C is held to the cup proper by means of pivoted or swinging wire links H—H, which are pivoted at H' to the body of the cup portion A, and at the other end 5 are clamped to the lever C by the ears or clips G—G. In this manner the attachment permits swinging about the pivot H' of the links and also permits the lever C to swing on the links at their upper end, trans- 10 versely connecting the two arms H—H, the spring wire being substantially in the form of a staple with inturned ends for pivots.

On one side of the lever C is the stop or 15 projection which engages the edge of the cup A' when the lever is thrown out of action or the valve released, so that the lower or closure end D of the lever moves in the arc of a circle with the fulcrum on the edge of the cup. Thus the end D of the lever will 20 clear the surface A', by making the cup surface substantially hemispherical.

On the opposite side of the lever C from the projection F, is embodied an opposite projection E nearer to the closure end D, 25 which is also adapted to engage the lip of the cup surface A', but on the opposite side from that engaged by the projection F. This projection E is adapted to limit the 30 swinging movement of the lever C in its locking movement and cooperates in the locking with the locking links H, which in the form shown are spring links.

Referring to the diagram in Fig. 3, it 35 will be seen that the normal length between the centers of the spring links is the distance between X and Y', which length is less than the combined distance between centers Y, Z—Z and X. Therefore in the movement of the lever C from the center line c' into the 40 vertical position on the center line a, the pivot between the spring links and the lever will move through the arc z, and thereby lengthen the distance from the pivoting center X, which causes a stretching of the 45 spring links H. This stretching of the links H puts them in tension, the maximum tension being reached as the lever passes the center line a, and in its further movement toward position c the tension in the spring 50 links is diminished, and in position h the links are in less than maximum tension, tending to force the closure in D of the lever C into its locked or sealing position. The lever is held with the links in position h by means of the stop E on the lever C, and the tension in the spring links H will thus 55 hold it in this position unless force is exerted on the upper end of the lever sufficient to overcome the additional strain of the tension in the links required to have the center line of the lever pass through the center line a at maximum tension. If force is applied 60 to release the lever, the moment it is moved past the center line a toward the releasing position, the tension in the spring links H

will snap it into completely unlocked position, and the momentum of the upper end of the lever, if given a sharp tap with the finger will cause it in the unlocking action to fulcrum on the projection F, and take the position as shown by dotted lines in Fig. 1. In order to prevent the lever from falling farther than as shown dotted in Fig. 1, the wall J' is fashioned to limit the movement of the lower ends of the spring 70 links H in their swing through the recess J,—thus preventing the lever from falling into a position where it would contact with the hot metal of the cylinder, and at the same time retaining it in an unlocked position 75 most accessible to be immediately and conveniently thrown into closing position when desired.

The closing end D of the lever is made substantially spherical and engages the edge 80 of the vent K, where it penetrates the bottom of the cup A'. This engagement will form a perfect seal, although if uneven, the action of the end D will constantly tend to wear the periphery of the vent to an even 85 seat. Any undue wear will furthermore not interfere with the perfect closure, because the tension of the wire links will accommodate any variation due to wear or manufacture to a predetermined degree sufficient 90 for any conditions of practical use.

The advantages of my invention will be better understood in comparison with priming cups and relief cocks when used, in 100 which a plug cock is common practice and which must have a tapered ground fit which is easily destroyed if the cock is forcibly turned. Such cocks stick because the lubricant is burned off when the flame is allowed to shoot through the relief cock for observing the quality of the combustion in the engine. When the lubricant is dried out owing to this heat the cock either leaks or is forced 105 into a sticking position, necessitating the use of wrench or pliers. This expedient results in breaking off the cock handle or otherwise injuring the entire device. When the cock sticks the contact is such as to cause heating of the cock handle with the danger of burning the fingers, which again 110 requires the use of pliers so that the ordinary cock handle which has been adopted from other practice, is really unsuited for 115 engine work.

In my relief cock and priming cup, it 120 will be seen that no sticking can result from the heating of the closure end of the lever, also the constant wear can only produce a better fit and more secure sealing of the vent, while the cock can always be operated 125 by hand, because a quick touch will immediately release it and when released it is in a position adapted to cool so as to be handled without danger when it is desired to relock it.

In reality the sealing end constitutes a ball valve engaging the edge of the vent hole, which in itself is a most simple, cheap and durable form of closure for this purpose.

The other parts of my device are equally simple and therefore relatively cheap to manufacture, combining at the same time durability, with the advantages of convenience and operation, added to which replacement and repair of parts is possible without difficulty. In the case of breakage or the loss of temper in the spring links, the same may be readily replaced, although the entire device can be made so cheaply that repairs would seldom be called for.

It will also be noted that when in closed position the lever C is in contact with the cup only at the end D, and the small end 10 of the projection E, affording the least possible chance for the conductivity of heat to the lever, which consequently will remain comparatively cool. Furthermore, when in the open position, the lower end, and in fact 15 the entire lever, swings to the side so as to be out of the way of the frame and permit the free exit of the gases. These features are of importance when compared with the ordinary relief cock when used, in which 20 the handle is contiguous with the valve having a large contact with the body of the petcock, thereby causing the handle to become very hot, and, on the other hand, the 25 hole in the valve barrel does not always register accurately with the vent when new, and upon the wearing of the valve is likely to become worse, thereby causing a restriction or interference to the gases, and frequently a variation in the effective vent on 30 the different cylinders.

It will be noted that various embodiments

in material, design and arrangement can be made in the practice of my invention which will still be within the scope of what I claim and desire to secure by Letters Patent.

I claim—

1. A combined priming cup and petcock for gasoline engines, comprising a body portion with means at one end for attachment to a cylinder and at the other end having a cup, a vent extending from the bottom of the cup, an oscillating member having one end adapted to cover said vent, said member constituting a lever, a spring link attached between the ends of said lever and having pivotal engagement with the body portion of the device, for the purpose described.

2. A priming cup for gasoline engines comprising a cup with a vent in the bottom thereof, a movable member having one end adapted to engage the bottom of the cup to seal said vent, a spring link to support said movable member and to permit its swinging about one end of said link and means of attachment of the link to the cup, permitting the turning thereof about the axis of attachment, a stop on one side of said movable member to arrest the swinging movement in one direction, whereby the movable member is brought to rest at a time when the spring link is at less than maximum tension.

In testimony whereof, I have signed my name to this specification, in the presence of two subscribing witnesses, this 15 day of Sept., 1914.

LARS G. NILSON.
